US00D638717S

(12) **United States Design Patent**
Schulman et al.

(10) **Patent No.:** **US D638,717 S**
(45) **Date of Patent:** ** *May 31, 2011

(54) **LIQUID CONTAINER**

(75) Inventors: **Bradley S. Schulman**, Glencoe, IL (US); **Andrew Edmund Kerley**, Ridgeway, CO (US)

(73) Assignee: **Green Planet Holdings, Inc.**, Chicago, IL (US)

(**) Term: **14 Years**

(21) Appl. No.: **29/342,676**

(22) Filed: **Aug. 28, 2009**

(51) LOC (9) Cl. **09-01**

(52) U.S. Cl. **D9/542**; D9/569; D9/571; D9/574; D9/559

(58) **Field of Classification Search** D9/434, D9/435, 452, 453, 454, 516, 520, 529, 545, D9/546, 549, 550, 551, 556, 558, 559, 563, D9/569, 571, 574, 530, 537-543; 215/381-385, 215/379; 220/600, 608, 660, 669, 675

See application file for complete search history.

(57) **CLAIM**

The ornamental design for a liquid container, as shown and described.

DESCRIPTION

FIG. 1 is a top, perspective view of a liquid container showing our new design;

FIG. 2 is a side elevational view thereof, the opposite side being a mirror image thereof;

FIG. 3 is a top plan view thereof;

FIG. 4 is a bottom plan view thereof; and,

FIG. 5 is a bottom perspective view thereof.

The broken lines shown in the drawings are for illustrative purposes only and form no part of the claimed design. All sides not shown form no part of the claimed design.
